UNITED STATES PATENT OFFICE.

GODFREY ENGEL, SR., OF BROOKLYN, NEW YORK, ASSIGNOR TO BUFFALO FOUNDRY & MACHINE CO., OF BUFFALO, NEW YORK, A CORPORATION OF NEW YORK.

CONDENSER.

1,399,294.

Specification of Letters Patent.

Patented Dec. 6, 1921.

Application filed March 1, 1920. Serial No. 362,477.

To all whom it may concern:

Be it known that I, GODFREY ENGEL, Sr., a citizen of the United States, and resident of Brooklyn, county of Kings, and State of New York, have invented certain new and useful Improvements in Condensers, of which the following is a specification.

The objects of my present invention are to improve and increase the efficiency of condensers and particularly to accomplish effective condensation with the use of a minimum amount of condensing water and without materially obstructing or retarding the flow of the vapors.

In a preferred form of my invention the condensing spray is produced by an overflow chamber which operates also as a spray head and as a means for creating another spray or film and part of the triple spray or films is caught in a collecting trough which spills a fourth set of separate and individual sprays over the vapor inlet. This collecting trough is of annular construction and is disposed about the inner wall of the condenser casing, which leaves the central portion of the casing practically unobstructed and open to permit free passage of the vapors operated upon.

Other novel features of construction, combinations and arrangements of parts will appear as the specification proceeds.

In the drawing accompanying and forming a part of this specification I have illustrated a practical embodiment of the invention, but wish it understood that variations and changes may be made without departure from the true spirit and scope of the invention as defined in the appended claims.

In the drawing referred to, Figure 1 is a vertical sectional view of the apparatus.

Fig. 2 is a horizontal sectional view of the same on substantially the plane of line 2-2 of Fig. 1.

Fig. 3 is a plan view of the sprinkler head construction as taken on substantially the plane of line 3-3 of Fig. 1.

Fig. 4 is an enlarged broken sectional view of the collecting trough.

The shell or casing of the condenser is designated 5 and the same is shown as provided in the upper or head portion thereof with a water inlet 6, and a vacuum outlet 7 and as provided at the lower end thereof with a drainage outlet 8 forming a column of the proper height.

Supported within the head portion of the casing is the spray mechanism consisting of a controllable overflow chamber having an annular liquid confining wall 9 and a bottom wall perforated to form a spray head 10. 60 This bottom wall is adjustable vertically and coöperates with the lower edge of the annular wall 9 to operate as a valve. In the construction shown, the spray head and the lower edge of the wall 9 are provided 65 with coöperating valve faces 11 and 12 inclined downwardly and outwardly to form spray discharge passages. This spray head is shown as adjusted by means of a rod 13 having a screw-threaded mounting at 14 70 and provided at its upper exposed end with a hand wheel or other suitable operating device 15. This rod may be provided with a suitable packing gland 16 at the point where it emerges from the casing. 75

At the upper edge the liquid confining wall 9 is shown as formed with teeth or serrations 17 so as to discharge the overflow in streams rather than in a solid sheet, over a conical deflecting flange 31. 80

It will be evident that by adjusting the spray head the discharge over the upper edge and the flow at the bottom portion of the overflow chamber may be readily governed and varied to suit different requirements, such as may be encountered in the handling of different vapors. 85

The annular wall of the overflow chamber is shown as supported by bolts 18 from a baffle plate 19 which is indicated as carried 90 by substantially radial ribs 20 on the under side of the top of the condenser casing. This baffle, in combination with the ribs, prevents the spray from being carried off with the vapor. 95

Below the spray mechanism described is arranged an annular collecting trough shown formed by means of an annular shelf 21 engaged and clamped between two of the sections of the casing at 22 and provided with 100 an upstanding flange 23 and a dependent flange 24, both spaced inwardly away from the inner wall of the casing. The upstanding wall is notched or serrated as indicated at 25 and similarly, the dependent wall is 105 toothed or serrated as indicated at 26. In this particular illustration the notches in the dependent wall are in vertical alinement with the points of the serrations in the upstanding wall as indicated in Fig. 4 and di- 110

viding ribs 27 are provided to insure separation of the streams issuing through the notches in the upper flange. This separation of the streams is further facilitated by 5 reason of the fact that the dependent points in the lower flange register with the notches in the upper flange so as to cause the separated streams to fall from the lower points, as indicated at the arrows 28. The notches 10 in the lower flange are preferably cut the full depth, or so far as the lower face of the shelf 21 (see Fig. 1), so as to prevent any of the vapor from "pocketing" beneath the trough.

15 29 designates the vapor inlet shown as opening through a portion of the downwardly and outwardly flaring wall 30 of the casing and as arranged to direct the vapors on a downward curve into the casing at a 20 point below and outside of the fall from the collecting trough.

With this construction the vapor is thus directed downwardly into the annular space within the casing about the fall from the 25 collecting trough and is required to pass in succession, first through this curtain of liquid and thence upwardly through the spray from the spray head and through the curtain delivered at the edge thereof and finally up 30 through the spray curtain at the upper edge of the overflow chamber. The vapor is thoroughly treated during such passage and the fact that the central portion of the casing is open and unobstructed, enables the 35 fluid extracted from the vapor to pass freely to the outlet without being materially retarded. This adds greatly to the capacity of the apparatus. This construction enables the spray to be directed outwardly so as to 40 cover the entire interior of the casing without any loss in efficiency because of the fact that the spray which contacts and runs down the sides of the casing is caught in the collecting trough and is by this trough brought 45 inwardly away from the walls and again discharged in position to freely operate on the vapor.

The condensation is facilitated by imparting a whirling motion to the spray. This is 50 accomplished in the illustration by mounting the spray head rotatably on the lower end of the supporting stem 13 and by providing the head on the upper face thereof with vanes or blades 32 curved or inclined 55 to cause the water passing through and over the head to impart a rotary movement thereto. This rotation of the spray head, it will be evident, causes both the streams passing through the head and the spray or film passing over the edge of the head to assume a 60 rotary or whirling motion, which results in the thorough treatment of all portions of the rising vapors.

By my invention it will be seen that the 65 spray mechanism in the head of the con-

denser produces at least three separate and distinct sets of sprays or films, first, the overflow at the top which is directed outwardly by the conical flange, second, the film issuing from between the valve faces 11 and 12 and third, the set of streams flowing through the spray head. And there is in addition to these sprays or films the fourth spray consisting of the separate streams overflowing from the annular collecting 75 trough. These several sets of sprays arranged as disclosed and assisted by the rotary motion described, result in a particularly effective condenser operation.

This construction results in a very thorough intermingling of the condensing water with the vapor and contact with the vapors throughout a longer period of time than has heretofore been possible and without the use of deflecting plates which obstruct the 80 flow of the vapors, thus effecting the condensation of the maximum amount of vapors with a minimum of injection water. The serrations in the liquid confining wall insure a substantially even discharge about the 85 periphery of the wall and the conical flange produces a film from these numerous streams.

The rotary movement of the spray head results in a further advantage in that it 90 makes the spray head self-cleaning.

What I claim is:

1. In combination, a condenser shell and spray producing means within said shell and comprising an overflow chamber having a 100 rotatable perforated bottom adjustable to vary the flow thereover and to vary the amount of overflow.

2. In combination, a condenser shell and spray producing means mounted therein and comprising a liquid confining wall, a rotatable spray head coöperating with the lower edge of said wall and means for adjusting said spray head with respect to the wall to vary the extent of flow between the spray 110 head and wall and to control the amount of overflow at the upper edge of the liquid confining wall.

3. In combination, a condenser shell and spray producing means mounted therein and comprising a liquid confining wall, a spray head coöperating with the lower edge of said wall and means for adjusting said spray head with respect to the wall to vary the extent of flow between the spray head and wall and to control the amount of overflow at the upper edge of the liquid confining wall, said spray head and the adjacent edge of the liquid confining wall having coöperating spray producing valve faces.

4. In combination, a condenser shell and spray producing means mounted therein and comprising a liquid confining wall, a rotatable spray head coöperating with the lower edge of said wall and means for ad-

- justing said spray head with respect to the wall to vary the extent of flow between the spray head and wall and to control the amount of overflow at the upper edge of the liquid confining wall, the upper edge of the liquid confining wall being serrated to divide the overflow into spray streams.
5. In combination, a condenser shell and spray producing means mounted therein and comprising a liquid confining wall, a spray head having a distributing flange, cooperating with the lower edge of said wall, means for adjusting said spray head with respect to the wall to vary the extent of flow between the spray head and wall and to control the amount of overflow at the upper edge of the liquid confining wall and a liquid inlet entered into the space defined by the liquid confining wall.
10. 6. A condenser comprising a casing, spray producing means therein, a vapor inlet below said spray producing means, an annular collecting trough disposed about the inner wall of the casing above the vapor inlet and provided with spill openings and with stream defining separations between said spill openings.
15. 7. A condenser comprising a casing, spray producing means therein, a vapor inlet below said spray producing means, an annular collecting trough disposed about the inner wall of the casing above the vapor inlet and provided with serrated upper and lower edges arranged with the cuts in the lower edge substantially in alinement with the points in the upper edge.
20. 8. A condenser comprising a casing, spray producing means therein, a vapor inlet below said spray producing means, an annular collecting trough disposed about the inner wall of the casing above the vapor inlet and provided with serrated upper and lower edges arranged with the cuts in the lower edge substantially in alinement with the points in the upper edge.
25. 9. In a condenser, a casing provided with spray mechanism in the upper portion thereof and an annular collecting trough below said spray mechanism and having an upstanding liquid confining wall and dependent stream directing teeth, the liquid confining wall having liquid outlets substantially in vertical alinement with said stream directing teeth.
30. 10. In a condenser, a casing provided with spray mechanism in the upper portion thereof, an annular collecting trough below said spray mechanism and having an upstanding
- liquid confining wall and dependent stream directing teeth, the liquid confining wall having liquid outlets substantially in vertical alinement with said stream directing teeth and stream defining ribs at opposite sides of said outlets.
11. A condenser comprising a casing and spray producing means therein including a perforated spray head provided with current producing vanes on the upper face thereof and means for supplying injection water to said upper face of the spray head.
12. A condenser comprising a casing and spray producing means therein including a perforated spray head provided with current producing vanes on the upper face thereof and means for supplying injection water to said upper face of the spray head and said spray head being rotatably supported to operate as a reaction spray distributing wheel.
13. A condenser comprising a casing and spray producing means therein including a perforated spray head provided with current producing vanes on the upper face thereof, means for supplying injection water to said upper face of the spray head and said spray head being rotatably supported to operate as a reaction spray distributing wheel, said spray head further having a distributing flange at the rim thereof and a wall coöperating with said flange to form an annular outlet passage or passages.
14. A condenser comprising a casing and spray producing means therein including a perforated spray head provided with current producing vanes on the upper face thereof, means for supplying injection water to said upper face of the spray head and said spray head being rotatably supported to operate as a reaction spray distributing wheel, said spray head further having a distributing flange at the rim thereof, a wall coöperating with said flange to form an annular outlet passage or passages and means for relatively adjusting the spray head and wall for varying the flow through said annular outlet passage or passages.
15. A condenser comprising a casing and spray producing means therein including a perforated spray head provided with current producing vanes, a wall coöperating with said spray head to form an outlet passage and means for relatively adjusting the spray head and wall to vary flow through said passage.

In witness whereof, I have hereunto set my hand this 26th day of February, 1920.

GODFREY ENGEL, Sr.
